UNITED STATES PATENT OFFICE.

CHARLES A. STELLER, JR., OF JERSEY CITY, NEW JERSEY.

FUSE OR ELECTRIC CUT-OUT.

No. 843,852.

Specification of Letters Patent.

Patented Feb. 12, 1907.

Application filed May 28, 1906. Serial No. 319,192.

To all whom it may concern:

Be it known that I, CHARLES A. STELLER, Jr., citizen of the United States, residing at Jersey City, in the county of Hudson and State of New Jersey, have invented certain new and useful Improvements in Fuses or Electric Cut-Outs, of which the following is a specification.

The present invention relates to an improved fuse or electric cut-out of that type which are commonly employed upon switchboards, panel-boards, knife-switches, &c.

The object of the invention is to provide a device of this character which is extremely simple and inexpensive in construction and which is peculiarly designed so that the fuse-wire can be easily replaced without the necessity of providing a new case and terminals.

For a full description of the invention and the merits thereof and also to acquire a knowledge of the details of construction of the means for effecting the result reference is to be had to the following description and accompanying drawings, in which—

Figure 1 is a perspective view of the improved electric cut-out with the cover removed. Fig. 2 is a longitudinal sectional view through the cut-out. Fig. 3 is a back view of the same, and Fig. 4 is a transverse sectional view on the line xx of Fig. 2.

Corresponding and like parts are referred to in the following description and indicated in all the views of the drawings by the same reference characters.

The numeral 1 designates the body of the case, which comprises the two ends 2 and the opposite sides 3, the upper and lower edges of the latter projecting slightly beyond the ends 2. At the top of the case the projecting portions of the sides 3 are formed with the grooves 4, within which the cover 5 is slidably mounted. At the opposite side of the case the projecting edges of the sides are connected by the bottom piece 6, the ends of which do not extend entirely to the end pieces 2 of the case, but are spaced somewhat therefrom. The terminals comprise the shanks 7, which fit against the rear faces of the ends 2, where they are held in position by the screws 14 and the heads 8, which project outwardly from opposite ends of the case and are formed with the slots or notches 9 for convenience in attaching the cut-out to the usual binding-posts. In the present instance the notch 9 at one end of the case is disposed longitudinally with re-

spect thereto, while the notch at the opposite end is disposed transversely, thus greatly facilitating the operation of removing or placing the cut-out in position. The inner ends of the shanks 7 are reduced in width at 10 and extend into the case through the spaces left between the bottom piece 6 and the ends 2. It will also be observed that these inner ends are bent upwardly and inwardly, so that their extremities are completely spaced from the inclosing walls of the case. A screw 11 is located at the extremity of each of the shanks 7, and these screws serve as a means for connecting the fuse-wire 12, which may be of any suitable size, according to the current which it is desired to carry. If desirable, plastic material 13, such as plaster, or paris, may be placed at the points where the shanks 7 enter the case in order to completely fill up any openings which may remain. When this case has once been placed in position, it will be apparent that when one fuse is blown a new fuse can be quickly and easily placed in position by simply slipping the cover 5 from the body portion 1 of the case and loosening the screws 11.

The case, including the body, cover, and bottom, is preferably constructed of some suitable dielectric or insulating material, such as hard rubber, papier-mâché, or other material adapted to be pressed or molded into shape.

Having thus described the invention, what is claimed as new is—

1. In a device of the character described, the combination of a case comprising end pieces and oppositely-disposed sides, a cover loosely mounted upon the case, a bottom, the ends of which are spaced from the before-mentioned end pieces of the case, terminals secured to the case, one end of each of the terminals extending into the case through the space formed between the bottom and the end pieces, while the opposite end of each of the terminals projects outwardly and is provided with means for forming a connection, and a fuse-wire having its ends detachably connected to the inwardly-extending ends of the terminals.

2. In a device of the character described, the combination of a case comprising end pieces and oppositely-disposed sides, a cover removably connected to the case, a bottom having the ends thereof spaced from the before-mentioned end pieces of the case, a pair of terminals, each of which comprises a

head and a shank, the shanks being secured to the end pieces and extending inwardly within the case, while the heads project outwardly and are provided with means for forming a connection, and a fuse-wire having its ends detachably connected to the inwardly-extending shanks of the terminals.

3. In a device of the character described, the combination of a case comprising end pieces and oppositely-disposed sides, a cover detachably connected to the case, a bottom having the ends thereof spaced from the before-mentioned end pieces of the case, a pair of terminals each of which comprises a shank and a head, the shanks being secured to the before-mentioned end pieces and projecting inwardly within the case, while the heads project outwardly and are provided with means for forming a connection, plastic material placed at the points where the shanks of the terminals enter the case, and a fuse-wire having its ends detachably connected to the inwardly-extending shanks of the terminals.

25 4. In a device of the character described, the combination of a case comprising end pieces and oppositely-disposed sides, the lower edges of the sides projecting somewhat beyond the end pieces, a removable cover for 30 the case, a pair of terminals each of which comprises a shank and a head, the shanks being secured to the end pieces between the before-mentioned outwardly-projecting edges of the sides and extending inwardly within 35 the case, while the heads are provided with

means for forming a connection, a bottom for the case, the ends of which are spaced from the before-mentioned end pieces, and a fuse-wire having its ends detachably connected to the inwardly-extending shanks of the terminals.

5. In a device of the character described, the combination of a case comprising end pieces and oppositely-disposed sides, the longitudinal edges of which project outwardly beyond the end pieces, a cover slidably mounted between the outwardly-projecting portions of the sides upon the front of the case, a bottom located between the outwardly-projecting edges of the sides upon the back of the case, the ends of the bottom being spaced from the before-mentioned end pieces, a pair of terminals each of which comprises a shank and a head, the shanks being secured to the end pieces between the outwardly-projecting edges of the sides and extending within the case where they are bent upwardly and inwardly and reduced in cross-section, while the heads of the terminals extend outwardly and are provided with means for making a connection, and a fuse-wire having its ends detachably connected to the inwardly-projecting portions of the shanks of the terminals.

In testimony whereof I affix my signature 65 in presence of two witnesses.
